(57) **CLAIM**

The ornamental design for an electric meter drawout case, as shown and described.

DESCRIPTION

FIG. 1 is a bottom front perspective view of the electric meter drawout case of the invention;

FIG. 2 is a rear perspective view of the electric meter drawout case illustrated in FIG. 1;

FIG. 3 is a front view thereof;

FIG. 4 is a top view thereof;

FIG. 5 is a right side view thereof;

FIG. 6 is a left side view thereof;

FIG. 7 is a bottom view thereof; and,

FIG. 8 is the rear end view thereof.
